Des. 218,822

Patented Sept. 29, 1970

218,822

FISH LURE

Melkiah E. Pope, 2527 Community Ave.,
Montrose, Calif.

Filed July 18, 1969, Ser. No. 18,258

Term of patent 14 years

Int. Cl. D22—07

U.S. Cl. D22—28

FIG. 1

FIG. 2

FIG. 3

FIG. 4

FIG. 5

FIG. 1 is a perspective view of my fish lure;
FIG. 2 is a side elevational view thereof;

FIG. 3 is a top view thereof;

FIG. 4 is an end view;

FIG. 5 is an end view thereof.

The characteristic feature of the design resides in the shape of the foot or shoe portion of the lure front wherein it is of generally maximum width at its rear end portion.

I claim:

The ornamental design for a fish lure, substantially as shown and described.
